Matthew L. Cimino, Esq.
Attorney

UNITED STATES PATENT OFFICE.

JOHN G. POOL, OF LYNN, MASSACHUSETTS.

MACHINE FOR MAKING WOODEN HEELS FOR BOOTS AND SHOES AND THE LIKE.

1,238,814.

Specification of Letters Patent.

Patented Sept. 4, 1917.

Original application filed May 15, 1915, Serial No. 28,465. Divided and this application filed November 15, 1915, Serial No. 61,682. Renewed August 10, 1916. Serial No. 114,302.

To all whom it may concern:

Be it known that I, JOHN GEORGE POOL, a citizen of the United States, residing at Lynn, in the county of Essex and State of Massachusetts, have invented a certain new and useful Improvement in Machines for Making Wooden Heels for Boots and Shoes and the like; of which the following is a full, clear, and exact description.

10 The object of this invention is to provide a jack for use especially in connection with the improved machine for making or turning wooden heels for boots and shoes, expeditiously, accurately and economically, 15 with the least possible manual labor or supervision on the part of the operative, and in a practically automatic manner, as set forth in the case filed May 15, 1915, Serial 20 No. 28,465, of which case this case is a division in conformity to the requirement of the Patent Office.

The invention consists of a jack, more especially designed for use in connection with the controlling and cutting mechanism 25 of the parent case referred to, which is adapted to admit of the ready and accurate placing of the work and its equally ready removal, and in which a lever mechanism is 30 used for clamping the work in the jack, said lever mechanism including a clamping-shoe carried by the jack-head and aligned with the work-rest and connected with a clamping-bar which is yieldingly supported 35 in the jack-head, and a clamping-lever for operating said bar and through it the shoe, as I will proceed now to explain and finally claim.

In the accompanying drawings illustrating 40 the invention, in the several figures of which like parts are similarly designated, Figure 1 is a side elevation of the jack, and showing also the cam-tracks of the machine of the parent case herein referred to. Fig. 45 2 is a front elevation. Fig. 3 is a partial vertical section. Fig. 4 is a perspective view of one of the cheek-pieces detached, looking at the inner side. Fig. 5 is an elevation of the jack-head detached. Fig. 6 is a partial 50 section and elevation illustrating a hold down for the jack.

1 is the jack-spindle, to which power may

be applied for turning the jack, and as illustrating one form of utilizing the jack reference is made to the parent case hereinabove referred to. This jack-spindle has formed on or applied to it a base-plate 2, the outer end of which is adapted to travel on a cam-track 3 in accordance with the invention of the parent case, and this base-plate is made or provided with a pair of parallel ears 4 at or near one end, and a pair of parallel lugs 5 about at its center, and a slot 6 beneath and between the lugs. Pivoted between the ears 4 is a lever 7 having a depending longitudinally slotted segment 8 which works in the slot 6 and between the lugs 5 and is pinned to the lugs by a pin 9 extending through the slot in the segment. This lever has applied to its outer end a cam-follower or shoe 10 which travels upon a cam-track 11, as in the case previously referred to, and said cam-follower is made adjustable up and down upon the lever 7 by means of a longitudinally slotted shank 12 and screw 13, or other suitable means, so that the lever and its superstructure may be arranged at the proper angle or elevation. The lever is provided upon opposite sides with the transverse guides 14 and 15, and between these guides are the upright cheek-pieces 16 adjustably secured to the lever as by slots 17 and screws or bolts 18. On the inner end 20 of the lever is the work-rest 19, having the end gage 20. Between the cheek-pieces is arranged the jack-head 21, which is adjustably held in between said cheek-pieces in any suitable way, as by the oblique slots 22 and bolts or screws 23. In order to hold the jack-head rigid and guide it in its adjustment in the cheek-pieces these cheek-pieces may be provided with the oblique lugs 24 fitting in the grooves 25 in the head. By this means the jack-head may be adjusted 25 longitudinally and vertically with relation to the jack-lever so as to conform to the style and height of heel-blank to be operated upon. The forward end of the jack-head is recessed at 26 and in this recess is arranged vertically the plunger 27, the lower end of which is slotted at 28 so as to receive a clamping-shoe 29, the rear end of which clamping-shoe is pivoted at 30 in a slot 31

in the jack-head so as to insure the proper positioning of the clamping-shoe with relation to the blank or work. The face of the clamping-shoe may have any suitable means 5 32 for gripping the blank or work, serrations being shown as one such means. The upper portion of the plunger is slotted at 33 and in this slot the clamping-bar 34 is pivoted at or near one end, the other end of said bar 10 being pivoted to a recoil device 35 arranged vertically in a socket 36 in the rear end of the jack-head 21 said clamping bar thus floating between the parts it connects or to which it is pivoted and being bodily movable. This recoil device may be a plunger 37 supported in the socket by a coiled or other spring 38, and it has a limited upward movement in the socket. A clamping-lever 39 is pivotally mounted in the jack-head 15 above the clamping-bar near its front, and has the cam end 40 adapted to act upon the clamping-bar to move it and its attached plunger 27 and by its eccentricity to lock these parts in clamping position, the recoil device serving to compensate for accidental variations in the height of the blanks for which the jack for the time being has been set, while sufficiently strong to effectively 20 clamp the blank. Beneath the clamping-bar is a spring-plunger 41 arranged in the jack-head and constantly pressing upwardly against said bar and serving to release the parts when the clamping-lever 39 is released. It will be seen by reference to Fig. 35 that the fulcrum of the clamping-lever 39 is in vertical alinement with the jack-spindle and above it so as to get a direct and supported thrust.

As will be seen, the jack members are well 40 supported laterally and vertically and thus rendered sufficiently rigid to meet the strains to which they are subjected in use.

As shown in Fig. 6, the jack-spindle may be hollow and contain a tension spring 42 45 reacting upon a rod 43 which is pivoted to the lower part of the jack-lever 7 and connected at its opposite end with an adjusting device 44 in the spindle so as to provide an adjustable downward tension for the jack, 50 and, for convenience, this device is herein referred to as a hold-down.

The jack and its spindle are designed to be bodily removable from the machine at pleasure.

55 The operation of the jack would seem to be obvious from the foregoing description. In Fig. 1, the blank 45 is shown clamped in position, while in Fig. 3 the full lines show the parts of the jack in open position for the 60 reception or renewal of the work, while the dotted lines show the clamping mechanism in clamping position as in Fig. 1.

In the machine of the parent case, referred to, the jack is designed to have a 65 rotary motion and also a vertical movement

on the cam-tracks so as to present the work to appropriate cutting-mechanism and also so that it shall be properly presented to the operator for the introduction and the removal of the blank.

It is to be understood that while the jack herein described was designed primarily for use on a machine for making wooden heels for boots and shoes, the invention is applicable to machines for manufacturing 75 other articles, and also for making heels of other material, and the claims herein are to be understood accordingly.

What I claim is:—

1. The combination of a jack-lever having 80 a work-rest, a jack-head carried by said lever, a clamping-shoe carried by the jack-head and alined with the work-rest, a clamping-bar connected with said clamping-shoe, means to yieldingly support said 85 clamping-bar, and a clamping-lever for operating said bar and through it the shoe.

2. The combination of a jack-lever having 90 a work-rest, a jack-head carried by said lever, a clamping-shoe carried by the jack-head and alined with the work-rest, a floating bodily-movable clamping-bar connected with said clamping-shoe at one end, a yielding support for said bar at that end, a recoil device connected with the other end of 95 said bar and responding to accidental variation in the height of the blank under the shoe, and a clamping-lever for actuating said bar.

3. The combination of a jack-lever having 95 a work-rest, a jack-head carried by said lever, a clamping-shoe carried by the jack-head and alined with the work-rest, a clamping-bar connected with said clamping-shoe at one end, a recoil device connected with the other end of said bar, a clamping-lever for actuating said bar, and a bar-lifting spring interposed between the jack-head and the clamping-bar.

4. The combination of a jack-lever having 100 a work-rest, a jack-head carried by said lever, a clamping-shoe carried by the jack-head and alined with the work-rest, a clamping-bar, a plunger sliding vertically in the jack-head and flexibly connecting the clamping-shoe and clamping-lever, means to yieldingly support the clamping-bar, and a clamping-lever for operating the bar and its connected parts.

5. The combination of a jack-spindle, base-plate thereon, a jack-lever pivotal mounted on the base-plate and having work-rest, a jack-head carried by said lever, a clamping-shoe carried by the jack-head and alined with the work-rest, a clamping-bar connected with said clamping-shoe, means to yieldingly support said clamping-bar, and a clamping-lever for operating said bar and through it the shoe.

6. The combination of a jack-spindle

base-plate thereon and movable therewith, a jack-lever pivotally mounted on the base-plate and having a yielding hold-down connection with said spindle and also having a work-rest, a jack-head carried by said lever, a clamping-shoe carried by the jack-head and aligned with the work-rest, a clamping-bar connected with said clamping-shoe, means to yieldingly support said

clamping-bar, and a clamping-lever for operating said bar and through it the shoe.

In testimony whereof I have hereunto set my hand this 18th day of October, A. D. 1915.

JOHN G. POOL.
